(57) **CLAIM**

The ornamental design for a combined brush and dock, as shown and described.

DESCRIPTION

FIG. 1 is a top, front perspective view of a combined brush and dock showing my new design.

FIG. 2 is a front view thereof.

FIG. 3 is a side view thereof.

FIG. 4 is top view thereof.

FIG. 5 is a rear view thereof.

FIG. 6 is bottom view thereof; and,

FIG. 7 is another side view thereof.

The broken lines in the drawings illustrate portions of the combined brush and dock which form no part of the claimed design.

1 Claim, 7 Drawing Sheets
